UNITED STATES PATENT OFFICE.

ALEXANDER MILNE, OF NEWARK, NEW JERSEY, ASSIGNOR TO NEWARK WATCH CASE MATERIAL COMPANY, OF NEWARK, NEW JERSEY, A CORPORATION OF NEW JERSEY.

WATCH HOLDER.

Application filed January 30, 1922. Serial No. 532,707.

To all whom it may concern:

Be it known that I, ALEXANDER MILNE, a citizen of the United States, and a resident of Newark, in the county of Essex 5 and State of New Jersey, have made and invented certain new and useful Improvements in Watch Holders, of which the following is a specification.

My invention relates to a watch holder, 10 and particularly to a holder which is adapted to enclose and support the popular priced so-called "dollar" watch, and thus allow it to be used on the dash or instrument board of an automobile, or in other 15 relations.

An object of my invention is to provide a holder which will be simple, and therefore cheap or economical to construct, and which will be adapted to support and provide 20 a mounting or setting for the so-called dollar watch, and which will be able or adapted to accommodate watches of different thicknesses.

A further object is to provide a watch 25 holder or watch mounting which is not only capable of holding watches of various thicknesses but will support them in such manner that they cannot be moved or tilted within the holder, and when once properly secured in place will remain permanently and rigidly so fixed.

A further object is to provide a holder 35 having a support for the watch at the center of the back, and which support thrusts the watch into engagement with an annular ring or opening and against the side walls of which the bezel of the watch engages, so that the watch cannot be tilted or rearwardly moved within the holder, although 40 the dial is plainly visible through the opening in the bezel-engaging portion or ring of the holder.

A further object is to provide a holder 45 which will accommodate watches of different sizes or thicknesses and in which a thrust is exerted against the rear or back of the watch, the line of force extending approximately through the center of the back, but the actual application of force being applied over a considerable circle, the center of which, however, coincides with the approximate center of the back.

A further object is to accomplish the 50 aforementioned ends in a simple and expeditious manner, the various parts being

readily susceptible to the ordinary machine or die operations, so that the entire holder may be economically manufactured, and with the foregoing and other objects in view, my invention consists in the improved 60 watch holder illustrated in the accompanying drawing and hereinafter described and claimed, and in such variations and modifications thereof as will be obvious to those skilled in the art to which my invention 65 relates, it being understood that changes may be made within the scope of what is claimed without departing from the spirit thereof.

The preferred embodiment of my invention is disclosed in the accompanying drawing, wherein:

Figure 1 is a view in front elevation of a holder embodying the characteristic features of my invention and supporting or 75 mounting a watch thereon;

Figure 2 is a sectional view taken on the line 2—2 of Figure 1;

Figure 3 is a rear view of my improved holder, the watch being removed therefrom 80 but the cross-bar or rear support being illustrated in place; and

Figure 4 is a view in section taken on the line 4—4 of Figure 3.

Referring specifically to the several 85 views, where similar reference numerals designate corresponding parts throughout, my improved holder is formed with the body or housing 10, which is secured to a supporting surface 11, in any preferred 90 manner, and preferably by providing the housing with an outwardly extending annular flange 12, through which extend the holding screws or fastening means 13.

The housing 10 is provided with the customary opening 14 for the accommodation of the stem and crown 15 of the watch therethrough and thus provides for the winding of the watch. The forward or front portion of the housing is turned inwardly, as at 16, and provided with the opening 17, and through which the dial 18 of the watch is visible. The side walls of the opening 17 are thus adapted to receive the bezel 19 of the watch thereagainst. 100

In order to accommodate and rigidly hold in position watches of varying thicknesses and to prevent the watch from tilting, I have provided the housing with the inwardly extending lugs or tongues 20, and 110

which are adapted to support the cross rod or strut 21 thereon, the said cross-piece extending diametrically across the housing, as clearly illustrated in Figure 3. The cross 5 strut or rod is provided with the central and threaded opening 23, through which extends the thumb screw 24, and upon the inner protruding extremity of which is pivotally mounted the disc 25. The disc 10 is pivotally held to the end of the thumb screw by reducing the diameter of the thumb screw, as at 26, and providing the disc with an opening through which the reduced portion 26 extends, and then turning over or enlarging the extreme end of the reduced portion 26, so as to form a pivotal rivet, as at 27. Thus the disc is allowed to turn with respect to the thumb screw, or is advanced or retracted as the 15 thumb screw turns, while the disc itself may be held against rotation.

With the parts as thus constructed, when a watch is placed within the housing, the thumb screw is retracted, and the bar or 20 cross strut then moved so as to be supported by and extend between the lugs or supports 20. The thumb screw is then turned and thus forces the disc 25 into engagement with the back of the watch. The thumb screw 25 is then forcibly tightened, which action takes place without rotating the disc, and therefore without marring the rear surface of the watch, and forces the watch forward, so that the bezel properly contacts with the 30 front and inturned portion of the housing, and against which it is rigidly held. The line of application of the rear force exerted by the thumb screw therefore passes through the approximate center of the back of the 35 watch, so that the watch is prevented from being moved rearwardly or tilted, should a force be applied to one portion of the dial. The slight resiliency of the cross-strut 21 insures that after the thumb screw has been 40 tightened it will remain permanently in such condition, and as the opening 14, through which the crown or stem of the watch must extend, must necessarily be bigger than the lower portion of the stem of the watch, any 45 slight sidewise play of the watch will turn the disc 25 but will not turn or tend to loosen the thumb screw 24, as the disc will rotate about the pivotal portion 27 of the thumb screw.

50 The disc 25 is preferably dished to a slightly greater extent than the curvature of the back of the watch, so that although the line of force of the rear holding member extends through the center of the back 55 of the watch, the actual application of the force is upon the circumference of a circle the center of which coincides with the center of the back, and thus the watch case is prevented from being locally compressed or 60 distorted, which might tend to interfere with

the proper working and timekeeping qualities of the watch.

Having thus described my invention, I claim and desire to secure by Letters Patent:

1. A watch holder comprising a housing 70 adapted to receive a watch therein and render the dial of the watch visible through the front thereof, means whereby the housing may be attached or secured to a supporting surface, a member extending across the housing and engaging the same so as to be supported thereby, and means associated with said member and adapted to exert a forward thrust upon the back of a watch contained within the housing. 75

2. A watch holder comprising a housing having an opening in the front so as to render a watch visible therethrough, and open in the rear so as to provide for the insertion of a watch therein, a member extending 80 across the housing, to the rear of the watch contained therein, engaging the housing and supported against rearward movement thereby, and means engaging said cross member and the back of the watch and adapted to exert a forward thrust against the back of the watch so as to secure the same in the 85 said housing.

3. A watch holder comprising a housing having an opening in the front so as to render a watch visible therethrough, and open in the rear so as to provide for the insertion of a watch therein, a member extending 90 across the housing, to the rear of the watch contained therein, engaging the housing and supported against rearward movement thereby, and means engaging said cross member and the back of the watch and adapted to exert a forward thrust against the back of a watch, the line of force 95 extending through approximately the center of the back of the watch, and the application of the force removed from said center. 100

4. A holder of the class described comprising a housing having an opening therein 105 for the reception of the stem of the watch and an opening in the front for rendering the dial of the watch visible, a member extending across the housing to the rear of the watch contained therein and engaging 110 and supported by portions of said housing, a thumb screw threadedly engaging said member and adapted to exert a forward thrust upon a watch and removably secure it within said housing. 115

5. A watch holder of the class described comprising a housing adapted to receive a watch therein and render the dial thereof visible, a cross member detachably engaging portions of said housing, a thumb screw 120 threadedly engaging said cross member, and a disc-shape member carried by said thumb screw and adapted to exert a forward thrust upon the watch within the housing. 125

6. A watch holder of the class described 130

comprising a housing adapted to receive a watch therein and render the dial thereof visible, a cross member detachably engaging portions of said housing, a thumb screw 5 threadedly engaging said cross member, and a disc pivotally secured to and carried by said thumb screw and adapted to exert a forward thrust upon the back of the watch contained within the housing.

Signed at New York, borough of Manhattan, in the county of New York and State of New York, this 26th day of January, A. D. 1922.

ALEXANDER MILNE.
